METHOD OF TREATING CRACKED HYDRO-CARBON GASES

Cary R. Wagner, Chicago, Ill., assignor to The Pure Oil Company, Chicago, Ill., a corporation of Ohio

Application February 29, 1932, Serial No. 595,748

8 Claims. (Cl. 196—10)

This invention relates to improvements in the art of treating hydrocarbon gases, obtained from cracking processes, to produce therefrom normally liquid hydrocarbon oils having the average boiling range of gasoline and which are characterized by the high percentage of unsaturated hydrocarbons they contain. The low boiling oils, produced in accordance with the invention, are particularly suitable for direct use as motor fuels or as blending agents in lower grade gasolines or motor fuels for the production of an anti-knock motor fuel of desired octane number.

In my prior application, Serial No. 354,426, I have set forth a process of subjecting cracked hydrocarbon gases, obtained by the conversion of high boiling hydrocarbon oils in the vapor phase at temperatures of the order of 1000° F. into low boiling oils, to heat treatment under regulated conditions of temperature and pressure, whereby to effect the formation from such gases apparently through polymerization of gasoline-like oils.

It is an outstanding object of the present invention to obtain similar oils from gases produced by cracking operations other than the low-pressure vapor phase type, especially cracked gases of the type developed by liquid phase or high pressure vapor-phase cracking operations. The cracked gases, formed by the operation of low-pressure vapor phase cracking processes are rich in ethylene, propylene and butylene and readily lend themselves to polymerization when heated to a temperature of approximately 900° F. and under pressures of the order of 300 to 1000 pounds per square inch. The cracked gases formed by the operation of liquid phase cracking systems, or in some instances high-pressure vapor phase systems, contain relatively smaller quantities of ethylene and its homologues and greater quantities of saturated hydrocarbons and, therefore, the gases of such cracking operations are not as adaptable for use in a gas polymerizing system as the low-pressure vapor phase type and do not form low boiling oils of desired anti-knock value.

The present invention, therefore, provides a system for treating gases formed by the cracking of oils in systems other than low-pressure vapor phase operations to extract from such gases through an absorption process or by other means the ethylene, propylene and butylene content thereof, whereby these latter hydrocarbons may be separated from the paraffin hydrocarbons and then subjected to polymerizing conditions to effect their formation into a high grade motor fuel.

For a further understanding of the invention, reference is to be had to the following description and the accompanying drawing, wherein:

The figure is a diagrammatic view, partly in section, showing a preferred form of apparatus by which the present invention may be carried out.

Referring more particularly to the drawing, the numeral 1 designates a tank or gas holder which is adapted to receive hydrocarbon gases produced as a result of the cracking or converting of high boiling hydrocarbon oils into lower boiling oils and, especially, the cracked gases discharged as fixed or permanent gas from oil converting systems especially of the liquid phase type. 10 In the cracking of oil in the liquid phase, relatively low temperatures are utilized, such temperatures being commonly of the order of from 750 to 875° F. In a typical liquid phase cracking operation, the oils at the temperatures specified 15 by the employment of high pressures are maintained substantially in the liquid phase for the required period of time necessary to effect the molecular decomposition of the high boiling hydrocarbons into the desired lower boiling hydro- 20 carbons. In contrast to this method of operation in the vapor phase cracking of high boiling hydrocarbon oils, the latter oils are subjected to temperatures of the order of 1050° F. while in the cracking zone, and the pressures on the oils 25 in the cracking zone are not sufficiently high to prevent the vaporization of the oils. Due to the higher temperatures used in a typical vapor phase cracking system, considerably greater quantities 30 of unsaturated hydrocarbons are present in the cracked oils and gases than are present in the corresponding constituents of a liquid phase operation and it is to the treatment of these liquid 35 phase cracked gases that the present invention is particularly directed, although in its broader 40 aspect, its general principles have application to gases resulting from the cracking of oils by any system.

Cracked gases of low olefine content (15 to 25%) are withdrawn from the holder 1 by way 45 of the pipe line 2 in which is arranged a pump 3 and these gases are introduced into the bottom of an absorption tower 4. The gases pass upwardly through the tower and are brought into intimate contact with a descending oil, or menstruum such as gas oil, solvent naphtha, cresol, high-boiling ketones or esters or other products capable of selectively dissolving olefines from such a mixture of olefines and paraffins, the 50 tower being maintained under a pressure of from 55

15 to 350 pounds per square inch, depending upon the solvent used and the concentration of olefines in the raw gas. The olefine hydrocarbons present in the cracked gas by this operation will be 5 absorbed in the heavy oil to a much greater degree than the paraffin hydrocarbon content or constituents of the gas. These gaseous paraffin hydrocarbons may be released from the upper part of the tower by way of a valved outlet line 10 5, while the solvent oil, with the absorbed olefine hydrocarbons, is withdrawn from the bottom of the tower by way of a valved transfer line 7.

The gas released from the top of the tower or column is relatively free from olefines and the 15 solvent at the bottom of the column has in solution a mixture of hydrocarbons in which the percentage of olefines is very much higher than in the original gas. Depending upon the analysis of the original gas, the solvent used and the pressure employed, this mixture may contain from 20 45 to 75% of olefines.

The mixture from the bottom of the absorption tower is pumped through the transfer line 7 to a suitable form of fire or steam heated still, for 25 example, a conventional tube still, where the mixture is subjected to distillation under temperatures of the order of from 300° F. to 600° F. and pressures varying between 600 and 1500 pounds, a pump 8 being disposed in the line 7 to secure these pressures, the still being designated by the numeral 9. The heated mixture discharged from the still 9 is passed into an evaporator 10, where gases and solvent separate, the solvent being taken out of the bottom of the 30 evaporator and transferred by means of a line 11, provided with a cooler 12, to the absorption column for reuse in said column.

The gases released from the top of the evaporator are passed without material pressure reduction 40 through a pipe line 13, which leads to a heating coil 14 disposed in a polymerizing still 15.

In order to form liquid oils from the olefine containing hydrocarbons which are thus delivered to the still 15, use is made of the polymerizing 45 system set forth in my above identified application and in my continuing application, Serial No. 573,233. Generally, such polymerization is secured by passing the gases directly from the evaporator 10 to the coil 14. In this coil, the 50 gases are heated to temperatures varying between 600 and 1000° F., while the same are maintained under pressures of the order specified in connection with the operation of the still 9, namely, 600 to 1500 pounds per square inch. These heated 55 products are then delivered to an externally located reaction drum 16, in which the polymerizing reactions are permitted to continue for the desired period of time. Since these reactions are highly exothermic in character, I prefer to use 60 the unheated externally located drum, which is removed from the influence of the highly heated furnace gases developed in the setting of the still 16.

It is desirable that the temperatures of the 65 products in the drum 16 should be carefully observed to maintain strictly polymerizing reactions and to avoid the overheating which would tend to produce cracking conditions and excessive coke formation.

70 The heated products discharged from the drum 16 may be cooled in the cooler 17 and thence conducted to a high pressure accumulator tank 18. The top of the tank 18 is connected with a gas outlet line 19 by which the olefine deprived 75 permanent gases are removed from the system.

The outlet line 19 may be provided with a pressure reducing valve 20 and the so-called permanent gas led to a tank, burner or other zone of storage or utilization.

The liquids formed by polymerization accumulate in the bottom of the tank 18 and are withdrawn by way of a pipe line 21, provided with a pressure releasing valve 22. The end of the line 21 contains a plurality of branches 23, which enter a stabilizing tank 24, which is adapted to "weather" or stabilize the liquids by removing therefrom excessively volatile compounds in the form of vapors or gases, particularly propylene or butylene fractions. These volatile fractions are led from the top of the tank 24 by way of a pipe line 25 and are conducted back to the gas inlet of the absorption tower 4 for further recovery of their olefine content, thus providing for the recirculation of such volatiles through the system and repeated treatment thereof. The bottom of the stabilizing tank 24 may be provided with a valved draw-off line 31 leading to a tank 32 in which the motor fuel distillate is received and stored.

While the system above described sets forth 25 a preferred embodiment of the invention, yet it will be understood that the invention is subject to considerable variation without departing from its underlying features. For instance, the system may be operated to distill gases from a solvent 30 obtained from the bottom of the absorption tower at lower pressures than those above specified and use a compressor to place the gases under the pressure necessary in the operation of the polymerizing still 15. In the preferred embodiment 35 of my invention, the use of such a compressor is rendered unnecessary and therefore the system may be operated more economically than if a compressor were employed.

Another alternative to which I may resort to 40 concentrate the olefine content of cracked hydrocarbon gas is to fractionate such gas under high pressure and/or reduced temperatures. In this manner the methane and hydrogen can be removed with the result that the remaining gases 45 contain enough olefines to carry on the desired polymerizing reactions in the still 15 and its associated drum 16.

Still, it is within the scope of the invention to 50 use solid adsorbents such as silica gel, activated carbon, fuller's earth and the like. In this same manner, partial fractionation is secured and the olefines concentrated sufficiently to adapt them to polymerization under the conditions of temperature and pressure specified in connection with 55 the still 15.

The following table sets forth an analysis of 60 various cracked hydrocarbon gases disclosing their relative olefine contents.

	Vapor-phase cracked gas low pressure	Gas removed from stabilizer tank	Cracked gas liquid phase Cross process	Cracked gas liquid phase Dubbs process	60
Methane+H ₂ ...	38.6	11.4	48.7	51.9	
Ethylen...	22.9	15.6	1.9	4.1	
Ethane...	11.9	12.3	19.4	19.8	
Propylene...	12.5	44.9	12.5	12.2	
Propane...	6.1		5.0	3.7	
Butylene...	8.1	13.8	6.2	5.5	
Butane...			3.0	2.4	70
C ₅ and heavier...		2.0	2.1	1.9	

From the above table, it will be noted that 75 gas produced by low pressure vapor phase cracking methods is particularly rich in the olefines

represented by ethylene and its homologues, whereas the corresponding compounds in gases produced by the operation of standard liquid phase cracking operations set forth have values considerably lower. However, by the use of the present invention, cracked gas obtained from such liquid phase operations may be treated so that prior to polymerization, it will contain olefines varying in quantity from 60 to 70%.

10 In view of the foregoing, it will be seen that the present invention provides a practical and economical method and means for treating cracked hydrocarbon gases, of the type produced particularly in the liquid phase cracking of oils, to obtain therefrom high yields of liquid oils suitable for use as improved motor fuels. The present invention renders it feasible and practicable to utilize these liquid phase cracked gases for use in a gas polymerizing system and thus transform them into hydrocarbons of greater economic value. It has been customary in the past to employ cracked gases resulting from liquid phase operations merely as fuel for use in oil refinery processes. The present invention 25 however enables a large percentage of these low value gases to be transformed into a superior grade of motor fuel.

What is claimed is:

1. The process of obtaining polymerized low-boiling liquid products of the gasoline boiling range from a gas mixture containing methane, hydrogen, and gaseous olefinic hydrocarbons which comprises compressing said mixture to 100-350 pounds/square inch above atmospheric pressure, contacting said compressed gas mixture with a petroleum hydrocarbon solvent having an average boiling range higher than that of gasoline and having a relatively low solvent power for methane and non-hydrocarbon gases under the working conditions, separating methane and other undissolved gases from said solvent charged with dissolved hydrocarbon gases, separating said dissolved hydrocarbon gases from said charged solvent, injecting said separated gases into a polymerization system maintained at a pressure of 600-1500 pounds/square inch above atmospheric, heating said gases in said system to a temperature about 700°-1000° F. and maintaining them at said temperature to effect conversion, cooling conversion products and separately recovering gasoline and unconverted gases.

2. The process of obtaining polymerized low-boiling liquid products of the gasoline boiling range from a gas mixture containing methane, hydrogen and gaseous olefinic hydrocarbons which comprises contacting said mixture while under pressure of 100 to 350 pounds per square inch with a petroleum hydrocarbon solvent having an average boiling range higher than that of gasoline and having a relatively low solvent power for methane and non-hydrocarbon gases

under the working conditions, separating methane and other undissolved gases from said solvent charged with dissolved hydrocarbon gases, separating said dissolved hydrocarbon gases from said charged solvent, injecting said last-mentioned separated gases into a polymerization system maintained under superatmospheric pressure, heating said gases in said system to a temperature suitable for effecting polymerization of the olefinic constituents of said gases to gasoline boiling hydrocarbons at the pressure to which the gases are subjected, cooling conversion products and separately recovering gasoline boiling range constituents and unconverted gases.

3. Process in accordance with claim 2 in which the undissolved gases are withdrawn from the system without being processed.

4. Process in accordance with claim 1 in which the conversion products are cooled while under superatmospheric pressure, the uncondensed gases separated from the condensed products, the normally gaseous constituents separated from the condensed products and recycled to the solvent treating step together with fresh gases charged to the process.

5. In a process in accordance with claim 1 the step of returning unconverted gases from the polymerization system to the solvent treating step together with fresh gases charged to the process.

6. Process in accordance with claim 1 in which the undissolved gases, after separation from the charged solvent, are withdrawn from the system.

7. In a process for polymerizing rich olefin-containing gases, to gasoline boiling constituents at pressures of 600-1500 pounds/square inch and at temperatures suitable for converting the gases to gasoline boiling constituents at the aforesaid pressures, the steps of cooling the conversion products and separating the gaseous from liquid components without substantial reduction in pressure, then materially reducing the pressure on the liquid components and separating the normally gaseous constituents therein from the normally liquid constituents, contacting under pressure of 100 to 350 pounds per square inch, the normally gaseous constituents with a petroleum hydrocarbon solvent having an average boiling range higher than that of gasoline and having a relatively low solvent power for methane and non-hydrocarbon gases under the working conditions, separating undissolved gases from the system, separating dissolved gases from the solvent and charging the latter gases to the polymerization process.

8. Process in accordance with claim 7 in which the temperature ranges from approximately 700 to 1000° F. and the gaseous constituents are contacted with the solvent at pressures of 15 to 300 pounds/square inch.

CARY R. WAGNER.
